SPREADER STOKER APPARATUS

Stuart H. Chapman, Lima, Pa., assignor to Westinghouse Electric & Manufacturing Company, East Pittsburgh, Pa., a corporation of Pennsylvania

Application June 16, 1943, Serial No. 491,019

2 Claims. (Cl. 110—115)

This invention relates to stokers, more particularly to those of the "spreader" or "sprinkler" type, and has for an object the provision of novel fuel-spreading mechanism of this type.

Another object of the invention is to provide a rotary fuel impeller so constructed as to be subject to minimum centrifugal forces.

A further object of the invention is to provide a rotary impeller for delivering fuel to a furnace, which impeller is of a construction providing for minimum distortion thereof resulting from exposure to the heat of the combustion chamber of the furnace.

Yet another object of the invention is to provide a rotary fuel impeller constructed mainly of structural members having high natural rigidity.

These and other objects are effected by the invention as will be apparent from the following description and claims taken in accordance with the accompanying drawings, forming a part of this application, in which:

Fig. 1 is a transverse sectional view through a spreader stoker mechanism embodying the principles of the present invention;

Fig. 2 is a fragmentary plan view of the structure shown in Fig. 1, with portions thereof broken away for the sake of clearness;

Fig. 3 is an enlarged fragmentary sectional view of a portion of the apparatus shown in Figs. 1 and 2 and taken along the line III—III of Fig. 4, looking in the direction of the arrows; and,

Fig. 4 is a sectional view taken along the line IV—IV of Fig. 3, looking in the direction indicated by the arrows.

Referring now to the drawings more in detail, and particularly to Figs. 1 and 2, the reference character 10 indicates, in its entirety, spreader mechanism for delivering fuel through the opening 11 in the front wall 12 of the furnace 13, to the grate structure 14 within the latter.

The spreader mechanism comprises a hopper 16 from which fuel discharges by gravity to the bottom plate 17 of the ram box 18. As shown more clearly in Fig. 2, the ram box is provided with a plurality of vertical partitions 19 extending from front to rear thereof and serving to space the series of rams 20, 21, 22 and 23.

Reciprocatory motion is imparted to the rams through a linkage arrangement comprising link 26 or 27 connected at one end to a ram and at the other end to one end of a bar 28, fixedly secured on the vertical shaft 30, which shaft is journaled for limited rotary motion in the lower and upper support plates 31 and 32, respectively, carried by

the ram box structure 18. Extending rearwardly from each vertical shaft 30 is a lever arm 34, disposed at right angles to the arm 28 and having its free end pivotally connected to the transversely-extending shaft or bar 35 by pins 36. Transverse reciprocatory motion is imparted to the bar 35 by suitable means, such as the engine 37, operating through the rod 38, having a slot and pin connection 39 with the bar 35.

In order to prevent clogging of the ram structure by fuel siftings working forwardly into the ram box, the latter is provided with an interior groove or recess 40 having inlet and outlet connections 41a and 41b, respectively, whereby air or liquid may be continuously passed through the groove 40 to remove siftings finding their way thereto through the joints between the rams and the ram box structure.

Fuel, pushed rearwardly from the bottom plate 20 of the ram box structure by reciprocation of the rams, moves over the supporting plate 42, upon which a plurality of spill plates 43, 44, 45 and 46 are adapted to reciprocate.

As best illustrated in Fig. 2, the number of spill plates preferably coincides with the number of rams, and the corresponding spill plates and rams are arranged to reciprocate in phase, that is, when ram 20 moves rearwardly its corresponding spill plate 43 likewise moves rearwardly. Also, it will be noted that alternate spill plates and rams (20, 43 and 22, 45) reciprocate in one direction when the remaining spill plates and rams (21, 44 and 23, 46) reciprocate in the opposite direction, this arrangement providing for more uniform feed of fuel than would be possible if all of the rams were advanced and retracted in unison. However, it will be apparent that corresponding spill plates and rams may be reciprocated out of phase and that all spill plates and/or all rams may reciprocate in unison or in any desired manner.

The means herein illustrated for reciprocating each spill plate comprises a rod 48 connected at its rearward end to the forward portion of the spill plate and having at its forward end a depending lug 49, which is bifurcated to receive the rearward end 50 of a connecting link 51, the end 50 being secured within the bifurcation of the depending lug 49 by the pin 52, for pivotal movement. The forward end of the link 51 is secured by pin 53 between the arms of the bifurcated lever 54, which is fixedly secured to the lower portion of the vertical shaft 30. Preferably, each member 54 is of double arm construction, and has attached to the other arm linkage similar to that just described, for operating the ad-

adjacent spill plate. Preferably, there is included in each link 51, suitable stroke-adjusting mechanism, indicated at 55. Inasmuch as the stroke-adjusting mechanism comprises no part of the present invention, it is indicated only schematically in the accompanying drawings.

In order that the spill plates may reciprocate freely beneath the fuel being fed rearwardly thereover, they are tapered at their forward edges, as at 58, with the result that they may easily slide beneath the fuel deposited upon the supporting plate 42. It will be apparent that reciprocation of the spill plates provides for feeding of fuel to the impeller or rotor mechanism 59, from points varying from rearwardly of the vertical centerline of the rotor to forwardly thereof, with the result that the fuel is projected through angles varying from the horizontal, thereby providing improved distribution of fuel lengthwise of the grate structure 14.

The impeller 59 is partially enclosed by a housing 60 disposed in close proximity to the path of the tips of the impeller blades. The impeller 59 comprises a pair of structural T-beams 61, disposed in parallel spaced-apart relation with the head portions 62 of the T's, adjacent each other, and with the web portions 63 lying in a common plane. A pair of end plates 64 are secured to and serve to space and support the T-beams 61, thereby providing a rotor structure in the form of a hollow rectangular frame. Where the length of the rotor renders it desirable, the T-beams may be braced, intermediate their ends, by cross members 65. The frame is supported by a pair of stub shafts 67, secured to and carried by the end plates 64 midway between the terminal portions thereof, the stub shafts 67 being supported, through the roller bearings 68, in bearings 69 carried by the end walls 70 of the impeller bearing casing 60. The outwardly-projecting stem portions 63 of the T-beams serve as securing and supporting means for blade members 71 connected to the stems 63 by suitable means, such as the bolts 72.

It will be apparent that this arrangement provides a fuel impeller which is relatively simple in construction, involves relatively small mass of metal to be subjected to heat from the combustion chamber to which it is exposed, and which is inherently rigid due to the T shape of the beams 61.

While the invention has been shown in but one form, it will be obvious to those skilled in the art that it is not so limited, but is susceptible of various changes and modifications without departing from the spirit thereof, and it is desired, therefore, that only such limitations shall be placed thereupon as are specifically set forth in the appended claims.

What is claimed is:

1. In a stoker, a rotary fuel impeller comprising a pair of stub shafts axially aligned in spaced-apart relation, a pair of end members connected at their centers to the adjacent ends of the stub shafts and lying in planes at right angles to the axis of rotation of the shafts, a pair of side members of T-section carried by the terminal portions of the end members in parallel relation to the axis of rotation of the shafts with the stems of the T-sections extending generally radially outward from the heads of the T-sections relative to said axis of rotation of the shafts, and fuel-impelling blades carried by said radially extending stems.

2. In a stoker, a rotary fuel impeller comprising a pair of T-beams disposed in parallel spaced-apart relation with the stems of the T's in a common plane and the tops thereof facing each other, a pair of end members connecting corresponding terminal portions of the T-beams, means supporting the end members for rotation of said end members and T-beams as a unit about an axis parallel to and midway of the T-beams, and a fuel-impelling blade carried by the stem of each T-beam.

STUART H. CHAPMAN.
